ADALBERT W. FISCHER, OF PHILADELPHIA, PENNSYLVANIA, ASSIGNOR TO SCHUTTE AND KOERTING COMPANY, OF PHILADELPHIA, PENNSYLVANIA, A CORPORATION OF PENNSYLVANIA.

TRIP-VALVE.

960,872.

Specification of Letters Patent. Patented June 7, 1910.

Application filed March 14, 1907. Serial No. 362,431.

To all whom it may concern:

Be it known that I, ADALBERT W. FISCHER, a subject of the Emperor of Germany, residing in the city and county of Philadelphia, in the State of Pennsylvania, have invented a certain new and useful Improvement in Trip-Valves, of which the following is a true and exact description, reference being had to the accompanying drawings, which form a part thereof.

My present invention relates to valves and particularly to a valve mechanism provided with means for moving the valve properly slowly in normal operation into and out of the position in which it closes the port controlled by it, and provided also with means for rapidly closing the valve when necessary in case of emergency, and the object of my invention is to improve the emergency valve closing means and also to combine the emergency closing means in a simple manner with the means for normally opening and closing the valve.

The various features of novelty which characterize my invention are pointed out with particularity in the claims annexed to and forming a part of this specification. For a better understanding of my invention, however, and the advantages possessed by it, reference may be had to the accompanying drawings and descriptive matter, in which I have illustrated and described one of the forms in which my invention may be embodied.

Of the drawings, Figure 1 is a sectional elevation with the valve in the closed position. Fig. 2 is an elevation taken at right angles to Fig. 1 of a portion of the valve operating mechanism. Fig. 3 is a view similar to Fig. 1 with the valve in the open position. Fig. 4 is a view taken similarly to Fig. 1 showing a modified construction. Fig. 5 is an elevation taken at right angles to Fig. 4.

Referring first to the construction shown in Figs. 1 to 3 of the drawings, A represents the valve casing having an inlet passage or chamber A¹ and an outlet passage or chamber A² separated by the partition A³ in which is formed the port A⁴ having on its upper side the valve seat A⁵. The port A⁴ is controlled by a compound valve comprising the main valve B and pilot valve D. The main valve B has attached to it the piston B¹ which slides in the hollow cylinder

C carried by the head C¹, the latter being secured in place by bolts and nuts C² to close an opening A⁶ in the valve casing through which the valve may be removed.

A restricted port or ports B² through the wall of the piston B¹ which is hollow permits a limited leakage from the valve passage or chamber A¹ into the interior of the cylinder C. This leakage may be supplemented by leakage between the piston B¹ and the wall of the cylinder.

The valve B is provided with a centrally located port B³ and valve seat B⁴ at the upper end of the port. The port B³ is controlled by the pilot valve D which when off its seat as shown in Fig. 3, opens communication between the interiors of the cylinder C and hollow piston B¹ and the under side of the valve B.

The pilot valve D is secured to the end of the valve stem E by a nut D¹ surrounding the stem above a flange E¹ formed at its lower end, the nut screwing into a threaded socket D² formed in the upper side of the valve D and receiving the end of the stem. The valve D forms a means for connecting the stem E to the main valve B, as the nut D¹ engages the lower end of a hollow boss B³¹ surrounding the stem E and secured to the valve B by bolts B⁴¹ to lift the valve B when the stem E is raised, and the valve D bears against the seat B⁴ to hold the valve B firmly against its seat when the valve is closed.

The stem E has secured to it a valve closing piston E² adapted to reciprocate in a cylinder C³ carried by the head C¹. A stuffing box C⁴ closes the lower end of the cylinder C³. Above the cylinder C³ is a head C⁵ provided with a stuffing box C⁶ for the portion of the stem E passing through it.

The portion E³ of the valve stem above the head C⁵ is threaded, the threaded portion passing through a nut F which is slidably but nonrotatably received in a bushing or cross head G supported from the head C⁵ as by the arms G¹ integrally connected at their upper ends to the bushing G and at their lower ends to the head C⁵. A lock in the form of a lever H, having its fulcrum pin H¹ journaled in ears G² projecting from the bushing or head G and a detent H² which may enter a recess F¹ formed in the adjacent side of the nut F normally holds the latter in the position

shown in Fig. 3, a bearing block F^2 being provided at the upper end of the recess to engage the detent. A spring actuated plunger H^3 is carried by the lever H which engages the cross-head G and tends at all times to hold the detent H^2 against the nut F . The lever H is connected by a rod I pivoted to it at I^1 to a reduced extension I^2 of the differential piston I^3 which slides in the cylinder C^7 formed in the valve head C^1 at one side of the cylinder C^3 . The upper end of the cylinder C^7 is closed by the elongated head C^8 which is formed at its ends with tight bearings for the piston extension I^2 .

The upper end of the cylinder C^3 is in relatively open communication with the valve chamber A^1 through ports C^9 and C^{10} formed in the head C^1 . A port C^{11} leads from the upper end of the cylinder C^3 to the upper end of the cylinder C^7 . The lower end of the cylinder C^3 is connected to a pipe J by a passage C^{12} . A relatively large branch passage C^{13} leads from the passage C^{12} to the lower end of the chamber C^7 . The exhaust pipe J is controlled by a suitable valve J^1 .

In the operative condition of the parts, the nut F is held in the elevated position shown in Fig. 3 by the detent H^2 and the valve may be slowly opened and closed by rotating the hand wheel K carried by the upper end of the stem E . When the valves B and D are both on their seats, the high pressure from the inlet chamber A^1 passing into the interior of the hollow cylinder C and hollow piston B^1 through the restricted leak port B^2 and between the piston and the inner wall of the cylinder C holds the valve B firmly against its seat. When thereafter the stem E is moved in the opening direction and the valve D lifted off its seat placing the interior of the cylinder C and hollow piston B^1 in communication with the low pressure chamber A^2 of the valve casing, the valve B becomes practically balanced and may be easily moved into the open position shown in Fig. 3.

The pressure on the piston E^2 is normally balanced by leakage allowed to pass by the piston from the upper end of the cylinder C^3 into the lower end, thus readily permitting the slow movement of the piston when the valve is opened and closed in the usual manner. The fluid thus leaking into the lower end of the chamber C^3 acts upon the lower and larger end of the differential lock controlling piston I^3 and maintains the lever H in position in which the detent H^2 enters the notch F^1 and locks the nut in its elevated position.

When in case of emergency the valve J^1 is turned to connect the pipe J to exhaust, the pressure is suddenly removed from beneath the lower ends of the pistons E^2 and

I^3 , the piston I^3 moves downward, unlocking the nut F , whereupon the fluid pressure in the upper end of the cylinder C^3 moves the piston E^2 rapidly downward and forces the valves B and D against their seats, thus effectually closing the port A^4 .

The position of the parts after the emergency closure of the valve in the manner just described, is shown by Fig. 1. To return the nut F from the position shown in Fig. 1, to that shown in Fig. 3, the hand-wheel K is rotated in the valve-closing direction; this rotation of the hand-wheel causes the nut to travel up the threaded valve stem portion E^3 , since the valve itself is then resting against its seat and hence incapable of further movement in the valve-closing direction. After the nut F has thus been returned to the position shown in Fig. 3, and the detent H^2 has been moved into the recess F^1 a subsequent rotation of the hand-wheel in the reverse, or valve-opening direction, opens the valve.

As the port C^{13} is larger than the portion of the port C^{12} between the lower end of the port C^{13} and the cylinder C^3 the piston I^3 moves to release the lock before the pressure on the piston E^2 becomes greatly unbalanced though the entire closing action is quite rapid.

It will of course be understood that the passages C^{13} and C^{12} are large enough so that any leakage past the pistons E^2 and I^3 will not affect the rapid movements of the pistons when the valve J^1 is opened. The valve J^1 may be operated by hand, or may be connected up to any suitable automatic mechanism, in ways well known to those skilled in the art. The use of a single controlling device, such as the valve J^1 for setting in operation the fluid actuating means for unlocking the nut F and for suddenly closing the valves is very effective in obtaining a rapid closing of the port A^4 whenever occasion requires. The lever H may of course be employed to lock and unlock the nut F when necessary.

In the form of my invention shown in Figs. 4 and 5, the fluid pressure actuated means employed in the construction first described to close the valve are replaced by resilient means which, when the valve is open, are at all times under compression, tending to close the valve when the lock lever H is tilted to release the valve operating stem. In the construction shown in Figs. 4 and 5 the nut F is provided at its upper end with a cross head F^3 from the opposite ends of which extend downwardly rods F^4 which pass through apertures formed for the purpose in ears G^3 projecting from the cross head G and carry at their lower ends adjustable threaded nuts F^6 . Between washers F^6 supported by the nuts F^6 and the under sides of the cross head ears G^3 , are

placed compression springs F' , which surround the portions of the rods F^4 projecting downward through the ears G^3 . These springs F' are under compression and tend 5 at all times to move the valve from the open position toward the closed position. The upper end of the cylinder C^7 is connected to the inlet side of the valve casing by a passageway C^{14} and the chamber C^7 below 10 the differential piston I^8 , is normally filled with fluid under the same pressure as that in the inlet side of the valve casing by leakage past the piston I^8 . The passage C^{18} leading from the lower end of the chamber 15 C^7 to the pipe J is not connected to a source of fluid under pressure, as in the construction shown in Figs. 1 to 3. A restricted passageway C^{15} supplies fluid under pressure to the chamber C . The operation of 20 this form of my invention is apparent in view of the foregoing.

Having now described my invention, what I claim as new and desire to secure by Letters Patent is—

25 1. In combination, a valve casing having chambers separated by a port, a valve controlling said port, a lock for positively holding said valve open, fluid pressure actuated means for closing said valve, including a cylinder, a piston moving in said cylinder and means for normally supplying both ends of said cylinder with fluid under pressure, and a single controlling device for releasing said lock and unbalancing the pressure on said piston to cause the latter to move and close the valve.

2. In combination a valve casing having chambers separated by a port, a valve controlling said port, mechanism which when 40 in operative relation forms a means by which the valve may be slowly moved into and out of the position to close its port, a lock normally holding said mechanism in its operative position and fluid pressure actuating means, including a common controlling device, for releasing said lock and rapidly closing said valve when said controlling device is actuated.

3. In combination a valve casing having 50 chambers separated by a port, a valve controlling said port, a screw and nut valve operating means, a lock normally holding said means in such relation to the valve that the latter may be slowly opened and closed by the operation of the screw and nut, fluid pressure mechanism, including a common controlling device, for releasing said lock and rapidly closing said valve when the controlling device is operated.

60 4. In combination, a valve casing having inlet and outlet chambers separated by a port, a valve controlling said port, a lock for positively holding said valve open, fluid pressure actuated means for releasing said lock, fluid pressure actuated means for clos-

ing said valve and a single device for controlling the operation of both of said fluid pressure actuated means.

5. In combination a valve casing having high and low pressure chambers separated 70 by a port, a valve controlling the port, a stem connected to said valve, a piston connected to the stem, a cylinder in which said piston moves, a lock for holding said stem in the valve-open position, a piston for operating said lock, a second cylinder in which the last mentioned piston moves, said cylinders having their ends from which the pistons move to unlock the stem and close the valve in relatively free communication with 80 the high pressure chamber and their opposite ends in restricted communication with the high pressure chamber, and means for connecting said opposite ends of the cylinder to exhaust. 85

6. In combination a valve casing having high and low pressure chambers separated by a port, a valve controlling the port, a stem connected to said valve, a piston connected to the stem, a cylinder in which said piston moves, a lock for holding said stem in the valve open position, a piston for operating said lock, a second cylinder in which the last mentioned piston moves, said cylinders having their ends from which the pistons move to unlock the stem and close the valve in relatively free communication with the high pressure chamber and their opposite ends in restricted communication with the high pressure chamber and means for connecting said opposite ends to exhaust, said means including a single actuating device. 95

7. In combination, a valve casing having high and low pressure chambers separated 105 by a port, a valve controlling said port, a stem connected to said valve, a valve closing piston connected to said stem, a cylinder in which said piston moves, a lock for holding said stem in the valve-open position, a differential piston for operating said lock, a cylinder in which said differential piston moves, said cylinders being arranged so that their ends from which the pistons move to release the lock and close the valve are in 110 relatively free communication with, and their opposite ends in restricted communication with the said high pressure chamber, and means for connecting said opposite ends of the cylinders to exhaust, the large area 120 end of said differential piston being adjacent the end of its inclosed cylinder, toward which the piston moves to release the lock whereby the normally unbalanced pressure acting on the opposite ends of the piston, tends to hold the lock in the locking position. 125

8. In combination, a valve casing having inlet and outlet chambers separated by a port, a valve controlling the port, a stem con- 130

nnected to said valve, a lock for holding said stem in the valve-open position, a valve closing piston connected to said stem, a cylinder in which said piston moves, a lock releasing piston connected to the lock, a cylinder receiving the lock releasing piston, the ends of said cylinders from which the pistons move to release the lock and close the valve being in relatively free communication with a source of fluid pressure and the opposite ends of the cylinders being in restricted communication with said source of fluid pressure, and means including a single actuating device, for opening said opposite ends of both of said cylinders to exhaust.

9. In combination, a valve casing having high and low pressure chambers separated by a port, a valve controlling said port, a stem connected to said valve, a lock for holding said stem in the valve-open position, provisions for closing said valve when the

latter is unlocked, a differential piston for operating said lock, a cylinder in which said differential piston moves, means for freely admitting fluid under pressure to the end of said cylinder from which the piston moves to unlock the valve and for admitting fluid under pressure in a restricted manner to the opposite end of the cylinder and means for connecting said opposite end of the cylinder to exhaust, the large area end of said differential piston being adjacent the end of its cylinder toward which the piston moves to release the lock, whereby the normally unbalanced pressure acting on the opposite end of the piston tends to hold the lock in the locking position. 25 30 35
